(57) **CLAIM**

The ornamental design for a dish as shown and described.

DESCRIPTION

1. Dish

1.1 : Perspective

1.2 : Front

The shape of the dish is conical, and the walls are initially steeper than the base for a short distance, then widen and continue in a conical shape toward the rim; on the outer surfaces of the sides of the dish, there are vertical parallel lines running from the base to the rim, and between these lines, in the center of the dish, there are circumferential geometric patterns.
